UNITED STATES PATENT OFFICE.

WILLIAM B. TUCKER, OF COLUMBUS, OHIO.

DESIGN FOR INDEX-PLATE AND NUT.

SPECIFICATION forming part of Design No. 16,874, dated August 24, 1886.

Application filed June 9, 1886. Serial No. 204,681. Term of patent 7 years.

To all whom it may concern:

Be it known that I, WILLIAM B. TUCKER, a citizen of the United States, residing at Columbus, in the county of Franklin and State 5 of Ohio, have invented a certain new and original Design for an Index-Plate and Nut; and I do hereby declare the following to be a full, clear, and exact description of the invention, such as will enable others skilled in 10 the art to which it appertains to make and use the same.

In the accompanying drawings, Figure 1 represents a plan of the back of a watch, showing the configuration of my design for an 15 index-plate and nut. Fig. 2 represents an enlarged detail view of the index-plate having the configuration of said design. Fig. 3 represents an enlarged detail view of the nut having the configuration of said design.

20 The leading feature of said design consists in the configuration and appearance of an index-plate and the nut which ordinarily occupies a position in front of said plate, the two uniting to produce a single effect on the eye.

25 It also consists in the configuration and appearance of the index-plate.

It consists, finally, in the configuration of the nut.

20 E designates the nut, which has an outline presenting a pointed top and two downwardly-extending inwardly-bent arms. These arms show partly below the curved lower line, g , of the index-plate. The remainder of the outline of the nut appears on the front of said 35 plate. The outline of the latter consists of

curved lower line, g , a straight top, and sides descending in successive steps g' from the latter to the former. The middle of the upper part of the face of the index-plate is occupied by a graduated scale, g^2 . The outline of the point 40 of the nut, E appears on said scale.

Having thus described my invention, what I claim, and desire to secure by Letters Patent, is—

1. The design for an index-plate and nut, 45 consisting in the straight upper border of said plate, the curved lower border thereof, the sides descending step by step from the former to the latter, the scale g^2 , and the superposed outline of the nut, having on top a point which 50 extends to said scale and downwardly-extending inwardly-turned arms, substantially as shown.

2. The design for an index-plate, consisting of an outline having a straight upper border 55 and a curved lower border, these being connected by side borders descending in successive steps, and the middle of the upper part of the face of said plate being occupied by a graduated scale, substantially as shown. 60

3. The design for a nut, E, having an outline with a point at the top and two depending inwardly-bent arms, substantially as shown.

In testimony whereof I affix my signature in 65 presence of two witnesses.

WILLIAM B. TUCKER.
